RAIL TOOL ATTACHMENT

John S. Bradshaw, Ivor, Va.

Application November 13, 1942, Serial No. 465,514

9 Claims. (Cl. 29—66)

This invention concerns a tool to hold and guide a chisel for cutting railway rails.

It is desirable for various reasons for one man to be able to cut a steel rail, but in cutting a rail with a chisel it is exceedingly difficult to hold a chisel firmly and hold it accurately in position.

Another difficulty in endeavoring to cut a rail is to avoid flying chips of steel that may be thrown off from the rail or from the chisel head.

A purpose to which this invention is directed is to arrange a holder that may apply a chisel to various portions of the steel rail to be cut. Such a holder is to be simple to arrange in position and is to be applicable for cutting a considerable line. The chisel is to cut the rail along the greater portion of the web and also along the base. In any given position moreover the chisel is to be held firmly. The chisel is to be gripped in such manner that a safety sleeve may be slipped into position to prevent chips from flying when the chisel is struck by a maul.

An important object is to provide firmness or rigidity in holding the chisel, but at the same time to provide for ready change in the position of the chisel-gripping elements.

In the accompanying drawing is illustrated a preferred embodiment of this invention and in the appended claims are pointed out features of novelty of the invention. The following description is directed to the preferred embodiment illustrated in the drawing, for the purpose of illustrating the broader features of this invention.

In the drawing:

Figure 1 illustrates in side view a preferred chisel holder in position on a steel rail;

Figure 2 illustrates in top view the chisel holder shown in Figure 1;

Figure 3 illustrates in side view the adjustment of the chisel holder to a position different from that shown in Figure 1 and particularly showing the chisel in nearly vertical position;

Figure 4 shows in vertical cross section an element of a holding block for the chisel taken along the line 4—4 of Figure 2; and

Figure 5 illustrates application of a flexible apron to prevent metal chips from flying from the edge of a chisel or from a rail when the chisel is applied.

According to this invention as illustrated, the chisel holder comprises a substantially built and angular body 1. This body is approximately L-shaped with an arm 2 of greater length than an arm 3. The arm 2 is adapted to retain a chisel while the arm 3 is adapted to hold a screw for tightening the holder against a rail to be cut.

The middle portion of the longer arm 2 affords a base for two clamps 4 and 5 that extend in generally opposite directions from each other.

One or the other of these clamps is adapted to be tightened against a head of the rail to be cut and thus to hold the longer arm in such position that a chisel 6 will be retained securely against the rail. The holder may be held by the companion clamp when the position of the chisel is altered. For example in general curved clamp 4 is adapted to hold the chisel 6 generally in horizontal position while the opposed curved clamp arm 5 is adapted to hold the chisel more nearly toward vertical position.

Somewhat more in detail and referring to Figure 1, the longer arm 2 is held in substantially horizontal position across the top of a rail. The curved clamp arm 4 extends downwardly with its terminal face 7 under the roll of the head of the rail 8. This assembly is retained in this position by a set screw 9 that extends through the short arm 3 to bear under the opposite bead of the top of the rail.

In order to add firmness to the structure and also to arrange for preliminary adjustment of the holder against the rail, a brace 10 is recessed into the side of the curved clamp arm 4. This brace 10 extends a way along the side of the rail bead 8 and thus minimizes side play of the holder. The arrangement of this brace 10 is illustrated in Figure 1 taken in conjunction with Figure 2.

Additional provision is included in this invention to minimize side play of the holder. This additional provision includes a brace 11 that extends to the side of the holder 1 to rest upon the top of the rail. This brace is also illustrated in Figures 1 and 2. Further strengthening of this element is derived from a vertical plate 12 that rests upon the broad top brace 11 and fits against the side of the long arm 2 of the holder. Thus a bracket is in effect maintained between the long arm 2 and the rail upon which it rests so as to steady the arm. Moreover, the two braces 10 and 11 guide the holder to a position in which the set screw 9 quickly may be tightened under the bead 8 of the rail to be cut.

Elements to hold the chisel 6 in position are illustrated in Figure 1 as presenting the chisel to the rail. For this purpose, the longer arm 2 of the holder is bifurcated into component arms 2A and 2B. The inner faces of these arms are channelled as illustrated in Figure 4. In these channels is fitted a guide block 13. This guide block is movable toward the rail or away from

the rail, riding within the channels of the side arms. At any position in these arms guide block 13 is locked against movement by compressing the arms against the block. This is accomplished by a bolt 14 that extends through proper openings at the ends of the tool arms 2A and 2B. If it is desired to alter the position of the block slightly a simple loosening of the bolt 14 permits this adjustment and similarly a simple tightening of the bolt and arms locks the block in position. 10

The block 13 contains a square opening from top to bottom through which is fitted a square arm 15. This arm grips the chisel. Adjustment of the arm 15 in its guide opening is made exceedingly simple by providing compression springs in the walls of the opening having faces to bear against a chisel-retaining arm 15. Two pairs of such springs 16 arranged opposite to each other are shown in Figure 2. These springs adequately hold the chisel in position, but permit quick alteration of the chisel to a slightly different position. Thus as the chisel cuts it may be advanced along the line cut. 15

The chisel 6 itself is held by adjustable arm 15 in a simple saddle 17 and tightened in the arm by a bolt head 18. The bolt head may simply be a threaded end of the arm 15 adapted to extend through a suitable hole in the chisel 6 and to retain a nut against the outside of the chisel. The saddle 17 may simply comprise a pair of 20 arms that are joined to a common base as in a Y or in an inverted V arrangement. This saddle may be pinned through the holder arm 15, and will afford some lateral support for the chisel 6 to a degree depending on the extent and position of the saddle arms 17. 25

The adaptability of this chisel holder is illustrated by a position of the holder as shown in Figure 3. In this position the chisel 6 instead of bearing against the web of the rail is held against the base of the rail and is in substantially vertical position. This is accomplished by applying the arm 5 which is located at a suitable angle opposite to the arm 4. The arm 5 bears a face 19 which when a horizontal portion of the arm 5 rests upon the top of the rail is tightened under the rail head by an opposing set screw 20. This set screw 20 conveniently extends through a suitable opening across the corner of the chisel holder at the junctions of the long arm 2 and the shorter arm 1 of the holder. 40

With the set screw 20 tightened to hold the arm 5 the chisel holder 15 extends nearly horizontally and therefore holds the chisel 6 down against the flange of the rail. As is apparent in Figure 3, the position of the chisel may be adjusted laterally by moving the arm 15 one way or the other against the grip of the compression spring 16. 45

The position of the chisel 6 as illustrated in Figure 3 makes clear an advantage of this arrangement in that to the top of the chisel may be fitted a flexible sleeve 21 to prevent chips from flying from the chisel. This sleeve 21 conveniently may be a piece of rubber tubing and conveniently may at its upper end receive a maul head 22. The maul head when struck in turn descends to strike the top of the chisel 6, but any chips from the head of the chisel are kept in the flexible tubing 21 and thus kept away from the operator. 50

Chips also may ordinarily be thrown off from the point of the chisel or from the cut being made. The present invention as illustrated in Figure 5 is adapted to prevent such chips from 75

injuring the operator. Figure 5 and also Figure 3 shows an apron 23 of flexible material and generally elongate, but being slit lengthwise and centrally. At the ends of the apron 23 are rigid retaining elements such as rods 24. These not only hold the ends of the apron, but also provide adequate rigidity to retain the apron in position. Thus, for example the chisel may be inserted through the slit in the apron. Then the lower rod 24 of the apron is held against the base of the rail being cut. The upper rod of the apron is held against the head of the rail and against the arm clamp 5. Thus the line of cut is covered by the apron so that chips may not fly upwardly toward the head of the chisel or toward the eyes of the operator. 10

This arrangement of a chisel holder is valuable because it permits use of the chisel by one man. The chisel may be arranged in position quickly to cut either the web or the base flange of the rail. The position of the chisel may be altered gradually as the cut proceeds. The adjustment of the chisel from a horizontal to a vertical position is made simply and quickly by tightening one or the other of the hooked arms under the bead of the rail to be cut. During use the chisel is held rigidly. The chisel is struck by a maul in a manner controllable by one man. 15

It is evident that this holder is adapted to retain other tools than a chisel; for example it may be used to mark or punch points along a rail. It will be evident to those skilled in the art that some variation is permissible in the position and extent of the curved arms 4 and 5 that grip the holder to the rail. 20

While I have in the above description disclosed what I believe to be a preferred and practical embodiment of the invention, it will be understood to those skilled in the art that the specific details of construction and arrangement of parts are subject to some latitude of variation without transcending the spirit and scope of the appended claims. 25

What I claim is:

45 1. A tool holder adapted for use in cutting railway rails comprising, a central arm, hook members extending from opposite sides of said arm, adapted to selectively grip under the head of a rail, said hook members being disposed at different angles, relative to said arm whereby the angular relationship between the central arm and the rail may be varied, said central arm having means to adjustably hold a tool against the rail. 50

55 2. A tool holder adapted for use in cutting rail- way rails comprising, a central arm, opposed hook members extending from said arm, each adapted to grip under the head of a rail, said hook members being angularly disposed relatively to one another whereby the angular relationship be- 60 tween the central arm and the rail may be varied, set screws opposed to said hook members to engage the sloping underside of the head of the rail to tighten the holder against the rail, said central arm having means to adjustably hold a tool against the rail. 65

3. A tool holder adapted for use in cutting rail- way rails comprising, an arm, a hook member extending from said arm to grip under the head of a rail, a set screw opposed to said hook mem- 70 ber to engage the sloping underside of the head of the rail to tighten the holder against the rail, and a flat brace extending from said arm to lie along the face of the rail in surface contact there- 75 with to position the holder on the rail, said arm

having means to adjustably hold a tool against the rail.

4. A tool holder adapted for use in cutting railway rails comprising, an arm, a hook member extending from said arm to grip under the head of a rail, a set screw opposed to said hook member to engage the sloping underside of the head of the rail to tighten the holder against the rail, a flat brace extending from said arm along the top of the rail and in surface contact therewith, a second brace extending from said hook member to lie flat along the side of the rail, the two said braces positioning the holder on the rail, said arm having means to adjustably hold a tool against the rail.

5. A tool holder adapted for use in cutting railway rails comprising, an arm having means to rigidly clamp it to a rail, said arm being divided beyond the clamping means to provide spaced parallel channel members, a block slideable between said channel members, and means to draw the channel members toward one another to bindingly hold the block in any position of adjustment, said block having means to adjustably hold a tool against the rail.

6. A tool holder comprising a clamp adapted to be secured to a railway rail, spaced parallel channel members extending from said clamp, a guide block having a central opening therethrough slidably mounted between said channel members, yieldable means extending from said guide block into said opening and a tool support positioned in said opening and frictionally engaged by said yieldable means.

7. A tool holder comprising a clamp adapted to be secured to a railway rail, spaced parallel channel members extending from said clamp, a guide block having a central opening therethrough slidably mounted between said channel members, adjustable means connecting said channels to determine the pressure against said guide block, yieldable means extending from said guide block into said opening, and a tool support positioned in said opening and frictionally engaged by said yieldable means.

8. A tool holder adapted for use in cutting railway rails comprising, an arm having means to rigidly clamp it to a rail, said arm being divided beyond the clamping means to provide spaced parallel channel members, a block slideable between said channel members, means to hold the block in any desired position of adjustment, means carried by the block to adjustably hold a tool support, the tool being attached to said tool support by means of a stud extending from said tool support and passing through an opening in said tool and a saddle surrounding said tool and secured to said tool support.

9. A tool holder adapted for use in cutting railway rails comprising, an arm, means to clamp the arm to a rail, means to support a tool in operative position, and a flexible sleeve having its ends surrounding respectively the upper end of the tool and the lower end of a hammer with which the tool is struck to prevent chips from flying.

JOHN S. BRADSHAW.
